No. 869,031.

PATENTED OCT. 22, 1907.

C. I. STOCKING.
LIGHTNING ARRESTER.
APPLICATION FILED JAN. 3, 1907.

UNITED STATES PATENT OFFICE.

CLARK I. STOCKING, OF HIAWATHA, KANSAS, ASSIGNOR OF ONE-HALF TO ARTHUR J. STEVENS, OF HIAWATHA, KANSAS.

LIGHTNING-ARRESTER.

No. 869,081.

Specification of Letters Patent.

Patented Oct. 22, 1907.

Application filed January 8, 1907. Serial No. 350,597.

To all whom it may concern:

Be it known that I, CLARK I. STOCKING, a citizen of the United States, and a resident of Hiawatha, in the county of Brown and State of Kansas, have invented 5 a new and Improved Lightning-Arrester, of which the following is a full, clear, and exact description.

The object of the invention is to provide a new and improved lightning arrester, which is simple, durable, compact and rigid in construction, dust and moisture 10 proof, and arranged to insure safe passage of an arc from a line to the ground without danger of setting fire to surrounding inflammable material.

The invention consists of novel features and parts and combinations of the same, which will be more fully 15 described hereinafter and then pointed out in the claims.

A practical embodiment of the invention is represented in the accompanying drawings, forming a part of this specification, in which similar characters of 20 reference indicate corresponding parts in all the views.

Figure 1 is a plan view of the improvement; Fig. 2 is an enlarged transverse section of the same on the line 2-2 of Fig. 1, and Fig. 3 is an enlarged longitudinal sectional elevation of the same on the line 3-3 of Fig. 1.

25 On a suitably constructed base A are secured binding posts B, B', B², B³ and B⁴, of which the binding posts B, B' are connected with the line wires C, C', while the binding posts B², B³ are connected with the instrument wires C², C³, and the binding post B⁴ is connected 30 with the ground at D. The binding posts B, B² are connected with each other by a lightning-arrester E, and a similar lightning arrester E' connects the binding posts B' and B³ with each other, and as both lightning arresters E and E' are alike in construction it suffices 35 to describe but one in detail. Each lightning arrester E and E' consists of a casing F, preferably of cylindrical shape and made of metal or other suitable conducting material, and within the casing F is held a conductor G of metal, carbon or a like conducting material, and, 40 between the conductor G and the inner surface of the casing F is interposed a non-conductor H having perforations, as plainly illustrated in Figs. 2 and 3. The ends of the casing F are closed by caps I and I' of rubber or other suitable insulating material, and on the 45 said caps I and I' are secured metallic contacts J, J' having their inner ends in contact with the ends of the conductor G, the outer ends of the clips being connected with brackets K, K' for engagement with a corresponding pair of binding posts B, B² or of B', B³. Now by the

arrangement described, a direct connection is made between the pair of binding posts B, B² and B', B³ to complete the circuits; but in order not to depend entirely on the lightning arresters E and E' for connection between the pairs of binding posts B, B² and B', B³, it is desirable to connect the said pair of binding posts with each other directly by connecting wires C⁴, C⁵, as indicated in Figs. 2 and 3. The casings F of the two lightning arresters E and E' are engaged at their outer surfaces by the curved ends of a spring bar L secured to a binding post N attached to the base A, and connected by a contacting plate O with the ground binding post B⁴ previously mentioned. Now in case lightning strikes either of the line wires C, C' then the electrical energy passing by way of the bracket K and contact plate J to the conductor G can readily pass through the perforations in the non-conductor H to the casing F, and from the latter by way of the spring bar L to the binding post N, plate O; binding post B⁴ to the ground at D. Thus the surplus electrical energy readily passes to the ground without danger to the instrument connected 6 with the wires C², C³, it being understood that the ordinary electrical energy sent through the line wires to the instrument readily passes through the lightning arresters E and E' without loss of energy owing to the insulating material H interposed between the conductor G and the casing F.

It will be noticed that the lightning arrester described is very simple and compact in construction and is completely dust and moisture proof, as the principal parts are contained within the casing F and the said 8 passage of the heavy electrical discharge can readily pass to the ground without danger of setting fire to the surrounding inflammable material.

Having thus described my invention, I claim as new and desire to secure by Letters Patent:

8 A lightning arrester, comprising a tubular casing of conducting material, and having caps of non-conducting material, a connection between the casing and the ground, a conductor within the said casing, a perforate tubular non-conductor interposed between the said conductor and the said casing, and contacts secured on the inner faces of the said caps and having their ends in contact with the ends of the said conductor, the outer ends of the said contacts being adapted for circuit connection.

In testimony whereof I have signed my name to this 9 specification in the presence of two subscribing witnesses.

CLARK I. STOCKING.

Witnesses:

F. M. PEARL,
ARTHUR J. STEVENS.
